LUMINAIRE

Giacinto C. D'Ercoli, Park Forest, Ill., assignor to McGraw-Edison Company, Milwaukee, Wis., a corporation of Delaware

Filed Feb. 7, 1968, Ser. No. 10,490

Term of patent 14 years

(Cl. D48—31)

Fig. 1

Fig. 3

Fig. 4

FIG. 1 is a front elevational view of a luminaire embodying the instant invention, the undisclosed sides being substantially the same in appearance.

FIG. 2 is a top plan view of the luminaire shown in FIG. 1;

FIG. 3 is a perspective view of the luminaire shown in FIG. 1; and

FIG. 4 is a fragmentary side elevational view of the luminaire shown in FIG. 1.

I claim:

The ornamental design for a luminaire, as shown and described.
